UNITED STATES PATENT OFFICE.

BENJAMIN FRANKLIN OREWILER, OF CHICAGO, ILLINOIS.

GARMENT-SUPPORTER.

1,152,753.

Specification of Letters Patent.

Patented Sept. 7, 1915.

Application filed June 20, 1912. Serial No. 704,780.

To all whom it may concern:

Be it known that I, BENJAMIN F. OREWILER, a citizen of the United States, residing at Chicago, in the county of Cook and State of Illinois, have invented a new and useful Garment-Supporter, of which the following is a specification.

The invention relates to improvements in garment supporters.

10 The object of the present invention is to improve the construction of garment supporters, more especially the construction of the button, or equivalent means for coacting with the garter loop, and to provide a simple and efficient device of strong and durable construction, adapted to be rapidly manufactured at an exceedingly low cost, and capable of being easily and quickly applied to the webbing by cheap unskilled labor and 20 without the use of expensive machines.

A further object of the invention is to provide a device of this character adapted to effect a saving in the webbing and adjustable to all thicknesses of hosiery without 25 injuring the same, and capable of retaining itself through resiliency within the contracted portion of the opening of an ordinary garter loop and of effecting a positive attachment to the hose of the wearer.

30 With these and other objects in view, the invention consists in the construction and novel combination of parts hereinafter fully described, illustrated in the accompanying drawings, and pointed out in the claims 35 hereto appended; it being understood that various changes in the form, proportion, size and minor details of construction, within the scope of the claims, may be resorted to without departing from the spirit or sacrificing any of the advantages of the invention.

In the drawings:—Figure 1 is a front elevation of a portion of a garment supporter, constructed in accordance with this invention. Fig. 2 is a longitudinal sectional view of the same. Fig. 3 is a transverse sectional view on the line 3—3 of Fig. 1. Fig. 4 is a detail perspective view of the device detached. Fig. 5 is a plan view of the blank, 45 showing the device before folding. Fig. 6 is a detail perspective view of the elastic disk or head. Fig. 7 is a front elevation of a portion of a garment supporter, illustrating another form of the invention. Fig. 8 is a 50 transverse sectional view on the line 8—8

of Fig. 7. Fig. 9 is a detail perspective view of the device shown in Figs. 7 and 8.

Like numerals of reference designate corresponding parts in all the figures of the drawings.

In Figs. 1 to 6 inclusive is illustrated the preferred form of the stud member, which is designed for use on the better class of merchandise. The device is constructed of a single piece of sheet metal, the blank 65 shown in Fig. 5 being stamped or otherwise formed and consisting of a central body portion 1 and opposite narrow portions 2, which are bent upwardly substantially at right angles to the central body portion at opposite 70 sides thereof and then inwardly over the body portion to form a flat or substantially oblong loop and the terminal portions of the metal, which are spaced apart at the top of the loop to render the latter resilient, and 75 bent to form approximately L-shaped spring arms 3, which form a stud. The loop or sleeve formed by the banding of the sheet metal is adapted to have a strip of webbing passed through it, as hereinafter fully explained.

The body portion of the blank forms the base or back of the webbing receiving loop, and it is provided at its inner end with a curved transversely disposed slot 4, having 85 a diagonal entrance opening 5 located at one side of the center of the slot and adapted to permit the webbing 6 to be readily introduced into the transverse slot 4. The curvature of the slot 4 spreads the webbing and prevents the same from crumpling together and thereby maintains the side edges of the webbing at the sides of the sleeve and away from the entrance opening 5 to prevent the webbing from accidentally passing through 95 the same and becoming disconnected from the device. The curved slot 4 and the diagonal entrance opening 5 form opposite approximately hook-shaped arms 4^a and 5^a of unequal length, the longer arm 5^a having a 100 segmental head 6^a presenting a curved inner edge and adapted to bow or flex the webbing.

While I have termed the strip 6 "webbing", it may be formed of tape or any 105 other suitable material as will be readily understood.

The outer end of the base or back of the sleeve is provided with a transverse slot 7 having enlarged terminal portions or eyes 110

7^a and provided with a downwardly extending lug or tongue 8 at the inner portion thereof to engage with the end portion of the webbing, which is passed upwardly 3 through the slot 7 from the rear face of the back and then around the outer portion 9 of the back or body and along the same to the inner slot 4. The webbing passes through the inner slot, being introduced into the 10 same through the diagonal entrance opening 5.

By this construction the device may be easily and quickly attached to the webbing without stitching, and cheap unskilled labor 15 may be employed as there are no expensive machines to be operated in assembling the parts. The strain on the flexible strip or webbing 6 tends to engage the same more securely with the device, and a great saving 20 in the material of the flexible strip or webbing 6 is effected with this form of the invention over those devices, which require a relatively long loop for their attachment.

The spring arms, which are spaced apart, 25 are provided with opposite notches 10, in which is arranged a disk or head 11 of soft rubber or other suitable material. The disk 11 is provided with a central opening 12 and the spring arms pass through the opening 30 and extend laterally in opposite directions at the outer face of the disk. The opening allows the angular heads on the arms to be passed therethrough and engage with and lie against the outer face of the 35 disk, whereby the disk is detachably retained on the arms in rear of the heads. By this construction a soft elastic head is provided for the device, and the latter possesses all the advantages of an ordinary rubber 40 button. The spring arms, which present smooth flat faces to the hosiery, are adjustable to accommodate the device to the thickness of the same, and the said arms through their resiliency are adapted to maintain 45 themselves positively in the contracted portion 13 of the opening of an ordinary garter loop 14, and the secure attachment of the hose is effected. The garter loop 14 is attached to the webbing in the usual manner 50 and confines the engaged portion of the hose on the head of the device. The outer side face of the spring arms are smooth and continuous from one side edge to the other, and they are arranged in parallelism with 55 the straight side walls of the garter loop, so that there is no tendency of the device to cut the hose as is the case where the latter is clamped against the edge of the metal or a relatively narrow surface. The head, being 60 soft and elastic, can be stretched so as to enlarge the hole 12 and allow its removal from and insertion upon the spring arms.

In Figs. 7 to 9 inclusive of the drawings is illustrated a simpler form of the invention, the inner and outer slots being omitted

from the sleeve 15, and the latter being preferably provided at opposite sides with V-shaped notches 16, which increase the resiliency of the device. When the device is in use and the spring arms are confined in 70 the reduced portion of the opening of the garter loop, they are partially compressed and cause the sleeve to frictionally engage and clamp the webbing. The sleeve 15 is provided with L-shaped spring arms 17 having 75 notches 18 for the reception of a rubber disk 19.

What is claimed is:—

1. In a garment supporter, a stud member 80 constructed of a single piece of sheet metal and comprising a back or base portion bent upwardly and inwardly at diametrically opposite points to form a flat sleeve, the terminal portions of the sheet metal being spaced to render the sleeve resilient and then 85 bent into outwardly extending approximately L-shaped spring arms, the latter being provided with opposite notches, and a rubber disk having an opening through which the arms extend, said disk being 90 seated in the said notches and forming a head.

2. A garment supporter including a plate 95 having a transverse slot and provided at one side of the center thereof and away from the end with a narrow diagonally arranged opening to permit a piece of webbing to be inserted in the slot, said plate being provided at the outer side of the slot with an inwardly curved edge merging into the slot 100 for holding the webbing away from the entrance.

3. In a garment supporter, a plate provided with oppositely disposed approximately hook-shaped arms of unequal length 105 spaced apart at their terminals and providing a transverse slot and forming an entrance opening at one side of the center of the slot, the longer hook-shaped arm having an approximately segmental head presenting a curved inner edge adapted to flex or bow a piece of webbing for holding the same away from the entrance opening.

4. In a garment supporter, a stud member 115 constructed of a single piece of sheet metal forming a back portion and then bent outwardly and inwardly over the back portion at diametrically opposite points and in spaced relation to form a flat open sleeve, the terminals of the metal being spaced from 120 each other on opposite sides of the center to render the sleeve resilient, and then bent into outwardly extending spaced approximately L-shaped arms forming a resilient stud, and a disk having an opening through 125 which the arms extend, the outer portions of the arms being arranged at the outer face of the disk and engaging the same to retain the disk detachably on the arms.

5. A stud member comprising a back pro- 130

vided at opposite sides with resilient portions bent inwardly over the back and then outwardly to form spaced spring arms, the terminals of which are bent laterally outward to form angular heads on the arms, and a rubber disk having an opening of less diameter than the combined diameter of the two heads of the arms when in their normal position, such opening allowing the angular heads to be passed therethrough and engage with and lie against the outer face of the disk, whereby the disk is detachably retained on the arms in rear of the heads.

6. A one-piece blank for a stud member comprising a body portion and relatively narrow arms or portions extending from the body portion at diametrically opposite

points, said body portion being provided at opposite sides of the center with slots, one of the slots being curved and the blank having a diagonal opening extending outwardly from the curved slot to the outer edge of the blank and the latter being provided at the other slot with enlarged terminal eyes and having a tongue at the inner side of such slot between the said eyes.

In testimony, that I claim the foregoing as my own, I have hereto affixed my signature in the presence of two witnesses.

BENJAMIN FRANKLIN OREWILER.
